UNITED STATES PATENT OFFICE.

FIRMAN R. CRIST, OF CLAYTON, NEW JERSEY.

DISPENSING-CONTAINER.

1,221,838.

Specification of Letters Patent. Patented Apr. 10, 1917.

Application filed March 10, 1915. Serial No. 13,425.

To all whom it may concern:

Be it known that I, FIRMAN R. CRIST, a citizen of the United States, residing at Clayton, in the county of Gloucester and 5 State of New Jersey, have invented certain new and useful Improvements in Dispensing-Containers, of which the following is a specification.

This invention relates to dispensing cans 10 and condiment holders, and more particularly to a new and improved lid therefor whereby the contents thereof may be easily delivered.

The primary object of my invention is to 15 provide means for easily and quickly controlling the delivery of the contents and to sift the same in process of delivery.

A further object of my invention is to 20 provide suitable means for maintaining the closure of my invention normally in closed position, and to provide means associated therewith for quickly and easily moving the same into open position.

A still further object of my invention re- 25 sides in the provision of a peculiarly constructed lid containing the embodiment of my invention and having associated therewith a cut-off member for controlling the egress of the contents thereof to scatter the 30 same when delivered. The construction of the device also is so designed as to prevent clogging of the openings through which the contents thereof are dispensed.

With the above and other objects in view 35 my invention resides preferably in the construction, combination, and arrangement of parts as hereinafter set forth, in the specification and illustrated in the accompanying drawing, in which—

40 Figure 1 is a perspective view of my improved lid for dispensing cans, the body of the can being shown broken away.

Fig. 2 is a bottom plan view of the lid.

45 Fig. 3 is a transverse sectional view taken on the line 3—3 of Fig. 2 looking in the direction of the arrow.

Fig. 4 is a detail perspective view of the actuating means.

Similar reference characters indicate 50 similar parts throughout the various views of the drawing.

Referring more particularly to the drawing in which the preferred embodiment of my invention is illustrated, the body of the dispensing can, condiment holder or the like, 55 is designated 1 and the lid or cover is indicated as a whole by the numeral 2. The lid 2 is of the usual flanged type, that is, having a face 3 and provided on its marginal edges with a down-turned flange 4 for engage- 60 ment with the upper marginal edge of the body 1 of the receptacle.

The face 3 of the lid is perforated in a peculiar manner, the perforations thereof extending in various lines of radiation from 65 a point on the face 3 eccentric to the center thereof. These perforations are designated 5 and are preferably elongated. From an inspection of Fig. 1 it will be noted that these lines of elongated openings extend 70 radially from a pin 6 as a central point. The pin 6 supports a cut-off plate 7, the said plate 7 being pivoted on the pin 6 and adapted for movement therearound within a limited distance. The cut-off plate 7 is 75 provided with a plurality of elongated apertures 8 similarly arranged to the apertures 5, but so positioned that when the plate is as shown in Fig. 2, the lines of radiation on which the apertures 8 are made will be out 80 of alignment with the lines of radiation of the apertures 5 so that the solid portions of the plate 7 will close the apertures 5. At a point substantially diametrically opposite to the pivot 6, the plate 7 is provided with an 85 arcuate slot 9, and a pin 10 carried by and depending from the under surface of the face 3 is engaged in the said slot 9 so as to assist in maintaining the plate 7 in snug engagement with the under surface of the 90 face 3. It will be understood that the curvature of the slot 9 is described from the pivot 6 as a central point. When the plate 7 is moved from the position shown in Fig. 2 in the direction of the arrow, the apertures 8 thereof will register with the complementally formed aperture 5 and thereby allow the contents of the receptacle to be dispensed and sifted in the process.

In order to quickly and easily move the 100 plate 7 from closed to open position and to maintain the same in normally closed posi-

tion, I have provided a means actuatable from the exterior of the lid 2 which comprises an actuating arm having an intermediate portion 11, the end portions thereof being secured at 12 and 13 to the plate 7 and the flange 4, respectively. The actuating member is substantially L shape, and is provided with an offset portion 14 substantially intermediate its length, the said offset portion 10 being adapted to extend exteriorly of the flange 4 and through an aperture 15 therein. The actuating arm is preferably formed of a strip of flat material, which may be of resilient material, and the inner end 16 15 thereof is twisted at substantially right angles to the intermediate portion 11 into parallelism with the face of the plate 7, and is provided with an aperture 17, by means of which it may be secured at 12 to 20 the plate 7, as hereinbefore mentioned. The resilient portion of the actuating arm should fall at a point designated 18 for a purpose which will hereafter be set forth. In normal position the parts are as shown in Fig. 25 2, and it will be noted that by exerting pressure inwardly upon the offset portion 14 motion will be imparted to the plate 7 in the direction of the arm against the tension of the resilient portion 18. This movement 30 will bring the apertures 8 and 5 into registration and permit of dispensing the contents of the receptacle. Releasing the offset 14 will allow the plate 7 to be drawn back into normal position, movement past a predetermined point being limited by means of lateral extensions 19 formed on the intermediate portion 11 of the actuating arm, these extensions 19 coming in contact with the peripheral flange 4 and preventing further outward movement of the actuating arm. It will be seen that the pin 10 hereinbefore mentioned serves to maintain the plate 7 in intimate contact with the under surface of the lid 2 and that particles of the 45 contents of the receptacle can not lodge themselves between the plate and the under surface of the lid 2 which would tend to clog and interfere with the operation of the closure.

50 The peculiar elongated formation of the openings is one of the principal features of my invention, it being seen that by this formation the same may be easily cleaned when necessary and will not become clogged with the contents of the receptacle, should the contents become damp, or from any other cause. It might also be stated that the pin 10 also co-acts with the lateral extensions 19 to limit the movement of the plate 7, 55 60 should the extensions 19 become damaged or not able to perform their functions.

From the above description taken in connection with the accompanying drawing, it is thought that the construction, use, and

advantages of my invention will be readily gathered, and it will be noted that the peculiar mounting of the cut-off plate 7, together with the novel arrangement of the apertures 5 and 8 affords a structure which is both simple and effective in its operation. 65 It will be noted that the fact that the plate 7 always returns to normal closed position is an advantageous feature of my invention, since this overcomes the element of forgetfulness which often enters into the unsuccessful operation of many of the prior inventions, in that, the prior devices very often do not afford a simple and convenient means for automatically returning the closure to normal closed position. 70 75 80

While I have shown and described my invention as possessing a peculiar form and construction, it is desired that it be understood that I may make such changes in the details thereof that do not depart from the spirit and scope of the invention as claimed. 85

Having thus described my invention what I claim and desire to secure by Letters Patent is:

1. A device as specified, including a lid member, a closure member pivoted to said lid member at a point eccentric to the center of said lid, said lid and closure members having a plurality of complementally formed apertures radially extending from the pivot point of said closure member as a center and registrable at times, means for limiting the movement of said closure member, means carried by the lid and in engagement with the closure member to actuate the same, means associated with said actuating means to return the closure member to normal closed position, and means for limiting the movement in said direction. 90 95 100

2. The combination with a dispensing container having an apertured lid and an opening in one side thereof, a closure pivoted to said lid at a point eccentric to the center thereof, apertures in the closure corresponding to the apertures of said lid, and a substantially right angularly bent spring arm connected to the closure and the container and having the intermediate portion thereof extending through the opening in the container side, whereby, the closure can be moved to open position by an inward pressure. 105 110 115

3. The combination with a dispensing container having an apertured lid and an opening in one side thereof, a closure pivoted to said lid at a point eccentric to the center thereof, apertures in the closure corresponding to the apertures of said lid, a substantially right angularly bent spring arm connected to the closure and the container and having the intermediate portion thereof extending through the opening in the container side, whereby, the closure can be moved to 120 125 130

open position by an inward pressure, and a plurality of lugs carried by the spring in proximity of the intermediate portion engageable with the inner face of said container side for limiting the outward movement of the arm.

In testimony whereof I affix my signature in presence of two witnesses.
